(57) **CLAIM**

The ornamental design for display screen mount, as shown and described.

DESCRIPTION

FIG. 1 is an isometric view of a display screen mount, showing our new design;

FIG. 2 is an isometric view thereof;

FIG. 3 is a front elevational view thereof;

FIG. 4 is a rear elevational view thereof;

FIG. 5 is a left side view thereof;

FIG. 6 is right side view thereof;

FIG. 7 is a top plan view thereof; and

FIG. 8 is a bottom plan view thereof.

FIG. 9 is an isometric view of a display screen mount, according to another aspect of our new design;

FIG. 10 is an isometric view thereof;

FIG. 11 is a front elevational view thereof;

FIG. 12 is a rear elevational view thereof;

FIG. 13 is a left side view thereof;

FIG. 14 is right side view thereof;

FIG. 15 is a top plan view thereof; and,

FIG. 16 is a bottom plan view thereof.

The dashed lines in the figures show the environment of the present design and are not part of the present design.

The broken away symbols in the drawings indicate that any portion of the display screen mount beyond what is shown forms no part of the claimed design.
